(57) CLAIM

The ornamental design for a hair color applicator, as shown and described.

DESCRIPTION

FIG. 1 is a top, front, right side perspective view of a hair color applicator showing the new design;

FIG. 2 is a top, front, right side perspective view of the hair color applicator of FIG. 1 at a different angle;

FIG. 3 is a left side view thereof; the right side view being a mirror image thereof;

FIG. 4 is a front elevational view thereof;

FIG. 5 is a top plan view thereof;

FIG. 6 is a bottom plan view thereof; and,

FIG. 7 is a rear elevational view thereof. The broken lines showing a container in FIG. 1 are for purposes of showing environmental structure only and do not form part of the claimed design. The broken lines showing holes along the teeth of the hair color applicator in FIGS. 1 through 4 are for illustrative purposes only and do not form part of the claimed design.
